PANTY

Tekla Bond, New York, N. Y.

Application October 17, 1952, Serial No. 21,877

Term of patent 14 years

(Cl. D3—17)

To all whom it may concern:

Be it known that I, Tekla Bond, a citizen of the United States of America, residing in New York city, county of New York, and State of New York, have invented a new, original, and ornamental Design for Panty, of which the following is a specification, reference being had to the accompanying drawing, forming part thereof, wherein,

Fig. 1 is a front elevational view a panty showing my new design.

Fig. 2 is a side elevational view.

Fig. 3 is a rear elevational view of same, and Fig. 4 is a bottom plan view thereof.

The zigzag edgings represent elastic.

I claim:

The ornamental design for a panty, substantially as shown and described.

TEKLA BOND.
